UNITED STATES PATENT OFFICE.

CHARLES E. DAVIS, OF CHICAGO, ILLINOIS, ASSIGNOR TO GOODMAN MANUFACTURING COMPANY, OF CHICAGO, ILLINOIS, A CORPORATION OF ILLINOIS.

MINING-MACHINE.

1,283,689.

Specification of Letters Patent.

Patented Nov. 5, 1918.

Application filed March 10, 1915. Serial No. 13,310.

To all whom it may concern:

Be it known that I, CHARLES E. DAVIS, a citizen of the United States, residing at Chicago, in the county of Cook and State 5 of Illinois, have invented a certain new and useful Improvement in Mining-Machines, of which the following is a specification.

This invention relates to mining machines and has for its object to provide a new and 10 improved device of this description particularly adapted to make a substantially straight face cut.

The invention is illustrated in the accompanying drawings, wherein—

15 Figure 1 is a vertical sectional view of the machine;

Fig. 2 is a sectional view taken on line 2—2 of Fig. 1;

20 Fig. 3 is a sectional view taken on line 3—3 of Fig. 1;

Fig. 4 is a diagrammatic view showing the machine in operation;

Fig. 5 is a view of the moving frame;

25 Fig. 6 is a view showing the flexible joint between two sections of the cutter arm;

Fig. 7 is a side elevation of the device shown in Fig. 6, with parts broken away;

Fig. 8 is a sectional view taken on line 8—8 of Fig. 7.

30 Like numerals refer to like parts throughout the several figures.

Referring now to the drawings, I have shown a main frame 1 mounted upon wheels 2, said wheels adapted to run upon rails 3.

35 A moving frame 4 is mounted upon the main frame. The moving frame 4 and the main frame 1 are pivotally connected together at one end by the pin 4^a. Upon this moving frame is mounted a motor 5, which

40 drives a gear 6. The gear 6 is loosely mounted on a connecting piece 7, into which project the ends of the shafts 8 and 9, said shafts being separately rotatable. (See Fig. 1).

45 The gear 6 is provided on opposite sides with the clutch members 10 and 11, which engage with the movable clutch members 12 and 13. The shaft 9 is provided with a worm 14, which drives a shaft 15 through the worm wheel 16. This shaft carries a drum 17 for a cable 18. The shaft 8 is

50 provided with a worm 19, which drives a shaft 20 by means of a worm wheel 21. The shaft 20 is provided with a bevel gear 22, which engages a bevel gear 23 on a shaft 24.

55 This shaft is provided at its other end with a

gear 25, which engages the teeth of a rack 26 on the main frame 1. The shaft 20 is also provided with a gear 27, which engages the teeth 28 on the connecting piece 29. This connecting piece is pivoted by the pin 30 with the projection 31 carried on the main frame and extending above the moving frame in Fig. 3. A pin 32 is attached to the connecting piece 29 and is movably mounted in the supporting frame 33, which supports 60 the cutting element 34. The supporting frame 33 is provided with a slot 35, along which slides a pin 36 fastened to the moving frame 4. This pin is preferably provided with a roller 37. The main frame 1 and the moving frame 4 are preferably provided 65 at their front ends with the cooperating guides 38 and 39. The supporting frame 33 is preferably provided at its front end with the downwardly projecting part 40 which 70 projects below the upper edge of the front end piece of the main frame. The supporting frame 33 is provided with the upstanding supports 41 which are provided with the racks 42. The cutting element 34 is provided 75 with pinions 42, which engage these racks. These pinions are connected with shafts 43, which are driven from the motor 44 on the cutting element through the bevel gears 45 and 46, the shaft 47, worm 48, 80 worm wheel 49 and shaft 50. (See Figs. 1 and 2). The cutting element is provided with a cutter arm 51. This cutter arm carries the cutter chain (not shown) carrying the cutters which cut the coal, the cutter 85 chain being driven by the sprocket wheel 52. This cutter arm as herein shown is provided with a flexible joint so that if the wheels of the main frame should drop off of the track while the device was in operation, the cutter 90 arm would bend at this flexible joint so as not to be broken by the weight of the machine. In the construction shown (see Figs. 6, 7 and 8) the cutter arm is provided with two sections 53 and 54. These sections are 95 flexibly hinged together, the hinge being near the machine so that it does not enter the cut in the coal. Any suitable flexible joint may be used. As herein shown, the section 54 is provided with a hinge member 55 having a hole therethrough, and the section 53 is provided with the two cooperating hinge members 56 and a pin 57 passed through these two members. The pin and hinge parts are arranged so that they do not 100

105

110

project into the guideway for the cutter chain. Attached to the sections 53 and 54 are the upstanding brackets 59 and 60. A pin 61 connects these brackets and is provided with the coil springs 62 and 63, the whole being arranged so that the section 53 may be moved up or down with relation to the section 54 provided said latter section is held. The springs may be adjusted by 10 the adjusting nuts 64 and 64^a.

In operating the device, the entire machine is moved up to the face of the coal and the cutting arm moved to engage the coal at the point where it is to be forced 15 therein. The cable 18 is then connected to a fixed point 18^a in front of the machine and the drum 17 rotated, thus causing the entire machine to be moved forward. During this process the cutter chain is operated 20 by the motor 44. When the cutter arm has been projected into the coal the proper distance, the drum 17 is stopped and the clutch member 12 moved to connect the motor 5 with the shafts 8 and 20. The rotation of the 25 shaft 20 causes a rotation of the shaft 24 and the gear 25, thereby causing the moving frame 4 to be moved about its pivotal point 4^a. At the same time the gear 27 engages the teeth 28 so as to move the connecting 30 piece 29 about its pivotal point 30, said connecting piece, through the agency of the connecting pin 32, carrying with it the supporting frame 33 which carries the cutting element. This produces both a lateral and 35 longitudinal movement of the supporting frame, due to the fact that the supporting frame is pivoted to the moving frame by the pivot 36. The two frames 33 and 4 move relatively during this operation, both laterally and longitudinally, and the longitudinal relative movement is taken care of 40 by the slot 35, the pin 36 moving along said slot. This combined movement causes the end of the cutter arm, after it has once been 45 forced into the coal, to be moved across the coal so as to make a substantially straight faced cut, as shown in Fig. 4. When the machine reaches the position illustrated in Fig. 4, the motor 5 is disconnected 50 from the shaft 20. The cable 18 is then placed on the other side of the machine, as shown in Fig. 4, and connected to a fixed point 18^b at the rear of the machine. The motor is then connected with the drum 17 55 and the operation of said drum causes the entire machine to be moved back so as to withdraw the cutter arm and finish the cut, the chain of the cutter arm being in operation during this movement. The supporting 60 frame 33 is provided with the guide wheels 33^a for the cable 18.

I have described in detail a particular construction embodying the invention, but it is of course evident that the parts may be 65 varied in many particulars; and I therefore

do not limit myself to the particular construction shown.

I claim:

1. A mining machine comprising a main frame, a moving frame pivotally connected 70 with said main frame, means for moving said moving frame about its pivotal connection, a supporting frame carried by said moving frame, a connecting piece, two separated pivots connected to said connecting 75 piece, one of said pivots connecting the connecting piece with the supporting frame, the other pivot connecting said connecting piece with the main frame, and means for moving said connecting piece so as to move 80 one end of said supporting frame, means for moving the other end of the supporting frame in the opposite direction, whereby said supporting frame is moved both longitudinally and laterally with relation to the 85 moving frame while the moving frame is in motion, and a cutting element connected with said supporting frame.

2. A mining machine comprising a main frame, a moving frame pivotally connected 90 therewith, a shaft on said moving frame, a driving part on said shaft, said driving part engaging a co-operating part on the main frame so that when the driving part is actuated the moving frame will be moved about its pivotal connection, a supporting frame mounted on said moving frame, a combined pivotal and sliding connection between the supporting frame and moving frame, means for moving said supporting 100 frame about its pivotal connection while the moving frame is in motion, a cutting element carried by said supporting frame, a cutter arm connected with said cutting element, and cutters connected with said cutter 105 arm.

3. A mining machine comprising a main frame, a moving frame pivotally connected with said main frame adapted to be moved about said pivotal connection, a supporting frame pivotally connected with the moving frame, and adapted to be moved about its pivotal connection, a supporting frame, a connection between the moving frame and the supporting frame comprising a pivot connected 115 with one of said frames and working in a slot in the other frame, an intermediate connecting piece pivoted to the main frame and having a pivoted connection with the supporting frame, means for simultaneously moving the moving frame and intermediate connecting piece so as to move the supporting frame and a cutting device on said supporting frame.

4. A mining machine comprising a main 125 frame, a moving frame mounted thereon, a pivot connecting the moving frame with the main frame, a supporting frame, a pivot connecting the supporting frame and the moving frame, said pivot free to move lon- 130

gitudinally with relation to said supporting frame, driving connections at both ends of said supporting frame for moving said ends in opposite directions, and a cutting element 5 connected with said supporting frame.

5. A mining machine comprising a main frame, a moving frame pivotally connected therewith, a shaft mounted on said moving frame, means for driving said shaft, a gear 10 connected to said shaft, a rack on the main frame engaged by said gear, a supporting frame mounted on the moving frame, a pivot connecting the supporting frame and

the moving frame, said pivot having a sliding connection with one of the frames, a 15 connecting piece pivotally connected with the main frame and the supporting frame, and means for driving said connecting piece.

In testimony whereof I affix my signature, in the presence of two witnesses, this 24th 20 day of February, 1915.

CHARLES E. DAVIS.
